DUST BAG FOR VACUUM CLEANERS

Lee N. Parks, Caro, Mich.

Application May 18, 1937, Serial No. 143,372

1 Claim. (Cl. 183—51)

This invention relates to dust bags for vacuum cleaners, a general object of the invention being to provide means for forming a relatively small conduit in the bag through which the dust laden air entering the bag must pass before it reaches the large chamber formed by the bag so that the velocity of the dust laden air is checked upon reaching the discharge end of the conduit and thus the major particles of dust and foreign matter are separated by gravity and fall into the lower part of the bag and are not whirled around in the bag with the air as occurs in bags not provided with the invention.

This invention also consists in certain other features of construction and in the combination and arrangement of several parts, to be herein-after fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is a sectional view through a bag with the tube therein.

Figure 2 is a view of a collar used for mounting the tube in the mouth of the bag.

Figure 3 is a section on the line 3—3 of Figure 1.

As shown in this drawing the conduit 5a is formed of a tube 15 of suitable material and this tube has its front end connected to a split collar 6 having prongs 7 thereon which are adapted to be pressed through the material at the neck of the bag and then over to connect the collar with the bag as shown in Figure 1. The collar is provided with the perforations 8 for receiving the stitching which connects the tube with the collar and the ends of

the band or collar 8 are connected together by the latch means shown generally at 18. A flexible member 17, preferably of elastic material connects the inner end of the bag to a button 19 in the bag so that the inner end of the tube is held elevated as shown in Figure 1.

This device can be readily put in place in bags now in use as the user of a vacuum machine can buy the tube and collar and readily place it in the bag of the cleaner. Thus the dust laden air 10 enters the bag and flows along the conduit with considerable velocity but as it passes from the conduit into the large part of the bag the velocity is checked so that the major particles of dust and foreign matter are separated by gravity when falling to the bag and are not whirled around in the bag as occurs in bags as now constructed. This invention also keeps the dirt away from the intake of the bag so that the motor of the vacuum device does not have to force the air into the bag against the dirt.

It is thought from the foregoing description that the advantages and novel features of the invention will be readily apparent.

It is to be understood that changes may be made in the construction and in the combination and arrangement of the several parts, provided that such changes fall within the scope of the appended claim.

What is claimed is:—

A conduit forming attachment for a dust bag comprising a tube of flexible material, a collar connected to one end of the tube and having spikes for engaging with the mouth of a bag and a member connected with the other end of the tube for holding the same in raised position in the bag.
